MACHINE CONTROL MEANS

Edwin A. Munschauer, Jr., Buffalo, N. Y., assignor to Niagara Machine & Tool Works, Buffalo, N. Y.

Application February 16, 1944, Serial No. 522,678

8 Claims. (Cl. 192—131)

1

This invention relates to novel control circuits for single stroke machines such as punch presses and the like.

The electric control circuit arrangement set forth herein and shown in the accompanying drawing provides a greatly simplified electrical means for the provision of what is known in the art as two-hand control. In providing tripping means for punch presses, metal shears, and similar machines, it is frequently desired to place a pair of push buttons in such relative position that the operator must use both hands to press both buttons to institute a cycle of operation. This is done for the obvious reason of insuring that the operator's hands are on the buttons and not in a dangerous or unsafe position. It has been found that operators, heedless of the safety provisions so made, tape down or "stake" one of the buttons in order to speed up or simplify their work.

The advantages of simplicity and security of operation inherent in the present novel circuit arrangement will be obvious to those skilled in the art from a perusal of the ensuing specification in conjunction with the accompanying drawing. While a particular adaptation is shown in detail herein by way of example, it is to be understood that the electrical control of the invention may be applied with like benefit to any kind of clutch or clutch tripping arrangement or, in fact, to any other machine controlling devices susceptible of control in an analogous manner. The principles of the present invention are not to be considered as limited in spirit or scope, otherwise than as defined in the appended claims.

In the drawing:

Fig. 1 is a fragmentary side elevational view of a punch press showing the crank shaft thereof and portions of the clutch tripping mechanism; and

Fig. 2 is a wiring diagram showing the novel electrical control circuits of the present invention.

In the drawing like characters of reference denote like parts throughout and the numeral 10 designates a punch press crank shaft having thereon a clutch 11. The details of the clutch are not shown since suitable single-revolution clutches are well known and may vary in detail. In common with most of the mechanical single-revolution clutches in use at present, a throwout pin 12 is provided and, as is well known to those skilled in the art, the throwout pin is pulled away from the clutch, to the right as viewed in Fig. 1, to cause the clutch elements to engage axially

2

and produce rotation of the crank shaft. The clutch elements are conventionally biased to engaging position by spring means, or otherwise. Upon release of the pulling impulse on the throwout pin, it is moved back to a position where it engages the clutch elements to cam the clutch elements to disengaged position so that the crank shaft is stopped at the end of a single rotation thereof.

10 From what has been said it will be seen that the throwout pin, after having been pulled, must be released substantially before the completion of a single rotation of the crank shaft if it is to declutch and stop the same at the end of a single revolution.

In the form illustrated by way of example, the clutch throwout pin 12 is pivotally attached to a rock arm 14 which has a central pivotal mounting 15 securing it to a punch press frame 16. The other arm of the rock arm 14 engages between a compression coil spring 17 and the end of a piston rod 18 of a piston 19. A casing 20 provides a fluid chamber 21 in which the piston 19 is disposed for axial movement and also supports and 25 houses the compression spring 17.

As shown in Fig. 1, the parts are in inactive position with the clutch released and spring 17 acts through the adjacent arm of rock arm 16 to retain piston 19 in its illustrated position. A 30 conventional solenoid operated valve shown in outline at 22 in Fig. 1 is adapted when its operating circuit is energized, to connect a fluid pressure source 23 to chamber 21 through a conduit 24, which moves the piston 19 to the left as viewed 35 in Fig. 1 and pulls the clutch throwout pin, through rock arm 14. When the operating circuit of the solenoid valve is de-energized, the valve moves to close off the pressure source 23 and vent conduit 24, whereupon spring 17 returns 40 the piston 19 to its illustrated position and clutch throwout pin 12 is returned to a position for disengaging the clutch at the end of an operating cycle of the crank shaft.

Fig. 2 schematically illustrates the control circuits for solenoid valve 22, which are so arranged that a separate manual two-hand push button pressing operation is required for each press cycle. That is, both buttons must be released and re-depressed, after a cycle has been instituted 45 by pressing both buttons and after the press cycle has been substantially completed, before a succeeding cycle can be begun. This positively prevents avoidance of the two-hand safety operation by tying down or "staking" one of the buttons. Means are further provided to prevent an

operator from releasing both buttons and re-depressing them during a press cycle to re-withdraw the throwout pin and cause the machine to continue on into a second cycle of continuous operation. Further, the proposed circuit arrangement is such that all circuits are open between press operations.

Referring to Fig. 2, supply conductors are designated 30 and 31 and the numeral 32 denotes the winding of solenoid valve 22. A pair of push buttons are indicated at 34 and 35, respectively, and it is to be understood that the push buttons are to be disposed at spaced points, such as at opposite sides of the front of the press frame, whereby an operator can depress both buttons only by employing both hands. Each button, when depressed, closes two switches, and the buttons are biased to return automatically to open position when manual pressure is removed. The button 34 controls switches 36 and 37 and button 35 controls switches 38 and 39.

It will be noted that an independent energizing circuit for solenoid valve winding 32 is present. The winding 32 connects with supply conductor 30, a conductor 42, the switches 37 and 39 which are connected in series, and a conductor 43 leading to the opposite supply conductor 31 and containing a normally closed switch 44.

A relay winding 46 connects with supply conductor 31 and has two parallel energizing circuits, one designated 47 and containing a normally open limit switch 48 and the other designated 50 and connecting in parallel with switches 38 and 39. A return conductor from the parallel-connected switches 36 and 38 is designated 51 and contains a normally open switch 52.

Both the normally closed switch 44 and the normally open switch 52 are under control of the relay winding 46. When winding 46 is de-energized the switches 44 and 52 are in their natural closed and open positions, respectively. Energization of winding 46 opens switch 44 and closes switch 52 and they remain in those conditions until the winding is again de-energized.

Referring to Fig. 1, a cam 55 is shown fixed to the crank shaft 10 and the numeral 56 designates a casing which houses the limit switch indicated at 48 in the wiring diagram, Fig. 2. The cam 55 has a lobe 57 which is so located that it engages a push button 59 of limit switch casing 56 to momentarily close limit switch 48 in passing. The timing of cam 55 is such that the limit switch 48 is momentarily closed toward the end of a cycle of crank shaft operation, but a sufficient distance from the end of the stroke to permit the throwout pin 12 to disengage the clutch by the end of a cycle of operation.

The operation of the foregoing control circuit arrangement will now be described. In the first place, it is essential that the operator depress both buttons 34 and 35 to close the series connected switches 37 and 39 to energize the winding 32 of the solenoid valve and pull the throwout pin 12 to initiate a cycle of crank shaft operation.

When the limit switch 48 closes momentarily, which as has been stated is preferably close to the end of the stroke to prevent release and re-depression of the buttons 34 and 35 before the end of the stroke, it establishes a circuit through conductor 47 which energizes relay winding 46 and opens normally closed switch 44 to break the solenoid valve winding circuit. The relay winding 46 simultaneously closes normally open switch 52 and if either of the parallel-connected switches 36

or 38 is still closed by reason of failure of the operator to remove his hands from both buttons, or because he has already re-depressed one or both buttons, or because either button has been "staked," a holding circuit for the relay winding 46 will be established through conductor 50, whichever of the switches 36 or 38 is closed, return conductor 51, and the holding circuit switch 52.

It is thus essential that both buttons 34 and 35 be released to open both switches 36 and 38 before it is possible to again close the solenoid valve winding circuit since this can be effected only through de-energization of relay winding 46 and consequent re-closure of the normally closed switch 44 in the solenoid valve winding conductor 43.

It will be noted that when buttons 34 and 35 are released, they close no circuits and that all auxiliary circuits are likewise open at all times when the push buttons 34 and 35 are in released position.

What is claimed is:

1. Control means for a machine having a single-revolution clutch including an element movable between clutch-engaging and clutch-disengaging positions, an electromagnet energizable to move said element to clutch-engaging position, means biasing said element to clutch-disengaging position, an energizing circuit for said electromagnet, a pair of switches connected in series in said circuit, a pair of spaced control elements manually movable to close said switches and energize said electromagnet, a relay and an energizing circuit therefor, a second pair of switches closable simultaneously with the first pair by manual movement of the control elements and connected in parallel in said relay circuit, a normally closed switch in said electromagnet circuit and a normally open switch in said relay circuit, said last two switches being movable by energization of said relay to open and closed position, respectively, a second normally open switch in series with said relay and in shunt with respect to said first normally open switch and means operable during the cycle of said single-revolution clutch to momentarily close said second normally open switch to energize said relay and establish a holding circuit therefor through said first normally open switch and either of said second pair of switches to de-energize the electromagnet through opening of the normally closed switch in its circuit in the event said circuit is then closed through said first pair of switches.

2. In a cyclic control for a machine having means movable between operating and non-operating positions, an electromagnet energizable to move said means to operating position, means biasing said means to non-operating position, an energizing circuit for said electromagnet, a pair of switches connected in series in said circuit, a pair of spaced control elements manually movable to close said switches and energize said electromagnet, a relay and an energizing circuit therefor, a second pair of switches closable simultaneously with the first pair by manual movement of the control elements and connected in parallel in said relay circuit, a normally closed switch in said electromagnet circuit and a normally open switch in said relay circuit, said last two switches being movable by energization of said relay to open and closed position, respectively, a second normally open switch in series with said relay and in shunt with respect to said first normally open switch and means operable

during the machine cycle to momentarily close said second normally open switch to energize said relay and establish a holding circuit therefor through said first normally open switch and either of said second pair of switches to de-energize the electromagnet through opening of the normally closed switch in its circuit in the event said circuit is then closed through said first pair of switches.

3. Control means for a machine having a single-revolution clutch including an element movable between clutch-engaging and clutch-disengaging positions, an electromagnet energizable to move said element to clutch-engaging position, means biasing said element to clutch-disengaging position, an energizing circuit for said electromagnet, a pair of spaced manually movable control elements and a switch means manually closable by each, said two switch means engaging said energizing circuit in series to require manual operation of both control elements to energize said electromagnet, a relay and an energizing circuit therefor, said two switch means being connected in parallel in said relay circuit, a normally closed switch in said electromagnet circuit and a normally open switch in said relay circuit, said last two switches being movable by energization of said relay to open and closed position, respectively, a second normally open switch in series with said relay and in shunt with respect to said first normally open switch and means operable during the cycle of said single-revolution clutch to momentarily close said second normally open switch to energize said relay and establish a holding circuit therefor through said first normally open switch and either of said switch means to deenergize the electromagnet through opening of the normally closed switch in its circuit in the event said circuit is then closed through said switch means.

4. In a cyclic control for a machine having means movable between operating and non-operating positions, an electromagnet energizable to move said means to operating position, means biasing said means to non-operating position, an energizing circuit for said electromagnet, a pair of spaced manually movable control elements and a switch means manually closable by each, said two switch means engaging said energizing circuit in series to require manual operation of both control elements to energize said electromagnet, a relay and an energizing circuit therefor, said two switch means being connected in parallel in said relay circuit, a normally closed switch in said electromagnet circuit and a normally open switch in said relay circuit, said last two switches being movable by energization of said relay to open and closed position, respectively, a second normally open switch in series with said relay and in shunt with respect to said first normally open switch and means operable during the machine cycle to momentarily close said second normally open switch to energize said relay and establish a holding circuit therefor through said first normally open switch and either of said switch means to de-energize the electromagnet through opening of the normally closed switch in its circuit in the event said circuit is then closed through said switch means.

5. Control means for a machine having a single-revolution clutch including an element movable between clutch-engaging and clutch-disengaging positions, an electromagnet energizable to move said element to clutch-engaging position, means biasing said element to clutch-

disengaging position, an energizing circuit for said electromagnet, a pair of switches connected in series in said circuit, a pair of spaced push buttons manually movable to close said switches and energize said electro-magnet, means yieldably biasing said push buttons to switch-open position, a relay and an energizing circuit therefor, a second pair of switches closable simultaneously with the first pair by manual movement of the push buttons and connected in parallel in said relay circuit, a normally closed switch in said electromagnet circuit and a normally open switch in said relay circuit, said last two switches being movable by energization of said relay to open and closed position, respectively, a second normally open switch in series with said relay and in shunt with respect to said first normally open switch and means operable during the cycle of said single-revolution clutch to momentarily close said second normally open switch to energize said relay and establish a holding circuit therefor through said first normally open switch and either of said second pair of switches to de-energize the electromagnet through opening of the normally closed switch in its circuit in the event said circuit is then closed through said first pair of switches.

6. In a cyclic control for a machine having means movable between operating and non-operating positions, an electromagnet energizable to move said means to operating position, means biasing said means to non-operating position, an energizing circuit for said electromagnet, a pair of switches connected in series in said circuit, a pair of spaced push buttons manually movable to close said switches and energize said electromagnet, means yieldably biasing said push buttons to switch-open position, a relay and an energizing circuit therefor, a second pair of switches closable simultaneously with the first pair by manual movement of the push buttons and connected in parallel in said relay circuit, a normally closed switch in said electromagnet circuit and a normally open switch in said relay circuit, said last two switches being movable by energization of said relay to open and closed position, respectively, a second normally open switch in series with said relay and in shunt with respect to said first normally open switch and means operable during the machine cycle to momentarily close said second normally open switch to energize said relay and establish a holding circuit therefor through said first normally open switch and either of said second pair of switches to de-energize the electromagnet through opening of the normally closed switch in its circuit in the event said circuit is then closed through said first pair of switches.

7. Control means for a machine having a single-revolution clutch including an element movable between clutch-engaging and clutch-disengaging positions, an electromagnet energizable to move said element to clutch-engaging position, means biasing said element to clutch-disengaging position, an energizing circuit for said electromagnet, a pair of switches connected in series in said circuit, a pair of spaced control elements manually movable to close said switches and energize said electromagnet, electromotive means and energizing circuit means therefor, a second pair of switches closable simultaneously with the first pair by manual movement of the control elements and connected in parallel in said electromotive circuit means, a normally closed switch in said electromagnet circuit and

a normally open switch in said electromotive circuit means, said last two switches being movable by energization of said electromotive means to open and closed position, respectively, a second normally open switch in series with said electromotive means and in shunt with respect to said first normally open switch and means operable during the cycle of said single-revolution clutch to momentarily close said second normally open switch to energize said electromotive means and establish a holding circuit therefor through said first normally open switch and either of said second pair of switches to de-energize the electromagnet through opening of the normally closed switch in its circuit in the event said circuit is then closed through said first pair of switches.

8. In a cyclic control for a machine having means movable between operating and non-operating positions, an electromagnet energizable to move said means to operating position, means biasing said means to non-operating position, an energizing circuit for said electromagnet, a pair of switches connected in series in said circuit, a pair of spaced control elements manually movable to close said switches and energize said

electromagnet, electromotive means and energizing circuit means therefor, a second pair of switches closable simultaneously with the first pair by manual movement of the control elements and connected in parallel in said electromotive circuit means, a normally closed switch in said electromagnet circuit and a normally open switch in said electromotive circuit means, and last two switches being movable by energization of said electromotive means to open and closed position, respectively, a second normally open switch in series with said electromotive means and in shunt with respect to said first normally open switch and means operable during the machine cycle to momentarily close said second normally open switch to energize said electromotive means and establish a holding circuit therefor through said first normally open switch and either of said second pair of switches to de-energize the electromagnet through opening of the normally closed switch in its circuit in the event said circuit is then closed through said first pair of switches.
